UNITED STATES PATENT OFFICE

CLYDE E. BROWN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT DETECTING MECHANISM FOR PICK AND PICK LOOMS

Application filed May 1, 1931. Serial No. 534,364.

This invention relates to a weft replenishing loom having two shuttle boxes at each side of the loom and using two shuttles which are picked alternately and successively, first in one direction and then in the other. Each shuttle lays one pick of weft or filling and then goes out of action for a single pick but lays a pick of filling in the opposite direction on the next succeeding pick.

10 It is the general object of my invention to provide an improved and simplified weft detecting mechanism by which the condition of the weft supply in the shuttle about to become active may be readily and reliably determined.

15 A further object of the invention is to provide means permitting the detecting mechanism to follow the rising or falling movement of the shuttle boxes during weft detection, and for automatically returning the detecting mechanism to an intermediate initial position after a detecting movement.

20 My invention further relates to arrangements and combinations of parts which will be hereinafter described and more particularly pointed out in the appended claims.

A preferred form of the invention is shown in the drawings, in which

25 Fig. 1 is a side elevation, partly in section, of portions of the loom having my invention applied thereto;

Fig. 2 is a detail sectional elevation, taken along the line 2-2 in Fig. 1;

30 Fig. 3 is a plan view of the parts shown in Fig. 1, and

35 Figs. 4 and 5 are diagrammatic side elevations showing the operation of my improved detecting mechanism.

40 Referring to the drawings, I have shown portions of a loom frame 10 and a lay 11 having upper and lower shuttle boxes 12 and 13 mounted for vertical movement as a unit in a lay end or frame 14. The shuttle boxes 12 and 13 are mounted at the upper end of the usual lifter rod 15, which is moved upward on one pick and downward on the next pick alternately and successively by any usual box mechanism.

45 Similar shuttle boxes and lifting mechanism are provided at the opposite end of the

loom (not shown) and a magazine and weft replenishing mechanism is also provided at the opposite side of the loom.

50 Upper and lower weft detecting devices 20 and 21 are mounted on spaced projections 22 and 23 on the side of a supporting bar 25, which is mounted for vertical sliding movement in a stand, or support 26 bolted to the loom frame 10.

An open wire frame 30 is pivoted in bearings 31 and 32 on the side of the fixed support 26 in position for engagement by the detecting members 40 or 41 of the upper and lower detecting devices 20 and 21.

55 These detecting devices 20 and 21 are of the side-slipping type, being so constructed that the detectors 40 and 41 swing to the left, as viewed in Fig. 3, in the direction of the arrow *a* and toward the tip of the bobbin B in the shuttle S or S'.

60 An indicating member 44 (Fig. 3) is connected by a link 45 to the outer upright portion of the swinging frame 30 and is adapted to be projected into the path of a floating lever 47 upon sidewise indicating movement 70 of one of the detectors 40 or 41.

65 The weft detecting devices 20 and 21 and the operating connections between these devices and the weft replenishing mechanism are all of a usual commercial type and in 80 themselves form no part of my present invention.

70 The detecting devices 20 and 21 are spaced apart on the support 25 a distance substantially equal to twice the distance between centers of the upper and lower shuttle boxes 12 and 13. The support 25 is provided with studs 50 and 51 positioned to enter a segmental slot 52 in a bracket 53 secured to the under side of the shifting shuttle boxes 12 and 13 and movable vertically therewith.

75 The lower end of the support 25 normally rests upon a plate 60, formed at one end of a lever 61 swinging about a fixed pivot or 85 stud 62 and having a weight W at the opposite end. The weighted end of the lever 61 normally rests upon a fixed support 63.

80 Having described the details of construction of my improved weft detecting mecha- 100

nism, I will now describe the operation thereof, with special reference to Figs. 4 and 5.

The slide or support 25 is normally supported by the lever 61 in the initial position indicated in full lines in Figs. 4 and 5. In this position, the lower weft detector 41 is opposite the lower shuttle S' if the shuttle boxes are in lowered position, and the upper weft detector 40 is opposite the upper shuttle S if the shuttle boxes are in raised position.

Assuming that the boxes are lowered as indicated in Fig. 4, the detecting member 41 will enter the lower shuttle S' as the lay moves forward, and the lower stud 51 will enter the segmental slot 52 in the bracket 53.

As the lay approaches front center, the boxes are shifted to bring the shuttle S' to its raised or running position, as indicated in Fig. 5. During this movement, the detecting device 41 will be raised by the bracket 53 to the position indicated at 41^a in Fig. 4. During such movement, the support 25 is raised away from the plate 60 of the lever 61. As the lay moves rearward after the boxes are raised, the support 25 is released and the support and detectors return by gravity to the normal position indicated in full lines in Figs. 4 and 5.

If the boxes are in raised position as the lay moves forward, the upper detecting member 40 enters the upper shuttle S, while the upper stud 50 is engaged by the segmental slot 52. As the boxes are thereafter lowered, the detecting device 40 moves to the position indicated at 40^a in Fig. 5. During this movement, the support 25 is depressed, raising the weight W. As the lay moves rearward and the stud 50 is released, the weight W returns the detecting device to initial or normal position.

It will be noted that one of the weft detectors always cooperates with the shuttle S or S' which is out of running position as the lay moves forward but which is about to be moved to running position. Consequently the shuttle which is indicated is always the shuttle which is about to become active and about to be picked to the magazine side of the loom, where weft replenishment may take place on the next forward beat of the lay.

Furthermore, while one detector is indicating, the other detector is entirely above or entirely below the shifting shuttle boxes and is thus inoperative.

With the simple construction herein described, I insure that the weft detecting mechanism will always indicate the shuttle about to become active and about to be sent to the magazine side of the loom, and I accomplish this result without the use of pattern mechanism or the setting of movable parts in selected positions.

Having thus described my invention and

the advantages thereof, I do not wish to be limited to the details herein disclosed, otherwise than as set forth in the claims, but what I claim is:—

1. In a weft replenishing, double-shuttle pick-and-pick loom having a lay, a pair of shifting shuttle boxes at each end of said lay, and means to shift said boxes after every pick of the loom, in combination, a pair of weft detecting devices at one end of the lay mounted on a movable support and vertically spaced apart a distance substantially equal to twice the vertical distance from center to center of a pair of shuttle boxes, means normally positioning said support and detecting devices as a unit vertically so that one or the other of said devices is opposite the shuttle about to become active, and means to cause said detecting devices and shuttle boxes to move vertically in unison as the boxes are shifted.

2. The combination in a loom as set forth in claim 1, in which means is provided to restore said support and detecting devices to initial position after a downward displacement thereof.

3. The combination in a loom as set forth in claim 1, in which said support and detecting devices are mounted for yielding movement in either direction from initial position, and in which means is provided for returning said support and detecting devices to initial position after a downward displacement thereof.

4. The combination in a loom as set forth in claim 1, in which said support and detecting devices are mounted for yielding movement in either direction from initial position, and in which said support and detecting devices return to initial position by gravity after displacement in one direction, and in which a counterweight is provided to return said support and detecting devices to initial position after displacement in the opposite direction.

5. In a loom, a pair of shifting shuttle boxes, a pair of weft detecting devices mounted on a movable support and spaced apart thereon a distance substantially equal to twice the center-to-center distance of said shuttle boxes, and yielding means to move said support to an initial position in which the upper detector is opposite the extreme high position of the upper shuttle box and the lower detector is opposite the extreme low position of the lower shuttle box.

6. The combination in a loom as set forth in claim 5, in which means is provided for moving said detectors vertically with the shuttle boxes during indication of weft exhaustion.

7. The combination in a loom as set forth in claim 5, in which means is provided for moving said detectors vertically with the shuttle boxes during indication of weft ex-

haustion, and in which yielding means is provided to restore said support and detectors to initial position after indication.

8. In a loom, a pair of shifting shuttle boxes, a pair of weft detecting devices mounted on a movable support and spaced apart thereon by a distance substantially equal to twice the center-to-center distance of said shuttle boxes, yielding means to move said support to an initial position in which the upper detector is opposite the extreme high position of the upper shuttle box and the lower detector is opposite the extreme low position of the lower shuttle box, one of said detectors being inoperative and the other detector engaging the shuttle which is out of running position, and means to move said detector with said shuttle to running position during weft indication.

9. In a weft replenishing, double-shuttle, pick-and-pick loom having a lay, a pair of shifting shuttle boxes at each end of said lay, and means to shift said boxes after every pick of the loom, in combination, a pair of weft detecting devices at one end of the lay mounted on a movable support and vertically spaced apart a distance substantially equal to twice the vertical distance from center to center of a pair of shuttle boxes, a pair of studs on said movable support, spaced apart a distance substantially equal to the center-to-center distance of said boxes, and a bracket carried by said boxes and having a segmental slot open at its front end and receiving one or the other of said studs as the lay moves forward.

In testimony whereof I have hereunto affixed my signature.

CLYDE E. BROWN.
